UNITED STATES PATENT OFFICE.

HENRY C. KNIGHT, OF GUNTER, TEXAS, ASSIGNOR OF ONE-HALF TO WM. B. BAKER, OF GUNTER, TEXAS.

PEDAL-OPERATING DEVICE FOR PIANOS.

1,165,681.

Specification of Letters Patent.

Patented Dec. 28, 1915.

Application filed January 11, 1915. Serial No. 1,658.

To all whom it may concern:

Be it known that I, HENRY C. KNIGHT, a citizen of the United States, residing at Gunter, in the county of Grayson and State 5 of Texas, have invented certain new and useful Improvements in Pedal-Operating Devices for Pianos, of which the following is a specification.

My invention relates to a pedal attachment for pianos and more particularly to a 10 pedal operating device adapted for the use of children in order that they may operate the piano pedals while playing; the same being readily positioned for use, adjusted 15 as necessary to the convenience of various persons, and readily removed when not longer required.

The invention also consists of certain 20 other novel features of construction and combinations of parts which will be more fully described and claimed, the same being shown in the accompanying drawings in which—

Figure 1 is a front elevation. Fig. 2 is 25 a side view. Fig. 3 is a plan view. Fig. 4 is a view in perspective of the locking device.

Referring to the drawings, the numeral 1 designates a portion of a piano which is 30 provided with the usual middle pedal 2 and the side pedals 3. As the pedal attachment hereinafter described is adapted for use with pianos of various forms and sizes, the piano and its usual adjuncts are shown 35 more or less conventionally.

The pedal operating attachment as shown, 40 comprises essentially two frame side pieces 4 and 5, respectively, which are spaced apart and joined by transverse rods 6 and 7 passing through suitable apertures in them, and the rods are threaded at both ends and fitted with nuts 8 and 9, between which the respective sides are clamped and supported. Vertically slidable and adjustable 45 between these side pieces is a heel rest 10, provided with downwardly extending supports 11 that fit loosely in the guides 12 of the inner surface of the sides; one edge of each support carries ratchet teeth 13, which 50 pawls 14 engage and retain the rest at any desired point vertically. Spaced apart and pivotally secured to the rod 7 are levers 15 that extend to the pedals 3 and upon the top sides thereof the ends are adapted to

rest. Similarly mounted on the rod 7 and 55 held adjacent thereto by collars 16 are levers 17 extending parallel therewith and terminating in foot pieces 18; a lug 19 projects inwardly from the side of the levers 15 in which are threaded thumb screws 20, the 60 ends of same resting against the lower edge of the levers 17 whereby the foot pieces may be adjusted vertically as desired. For detachably connecting the device with a piano, the side members 4 and 5 are provided with 65 thumb screws 21 which may be pointed and adjusted so that when the front of the device is raised and the ends placed beneath the piano, and the device then rested upon the floor, will cause the pointed screws to 70 slightly enter the bottom of the piano, thus securing it against easy movement.

At times in the practice of a pupil it is desirable that the use of the pedals be discontinued; so a locking device is provided 75 consisting of a bar 23, extending from one side of the frame to the other and loosely pivoted therein. Formed integrally with the bar are wings 24, that when turned downward permit the free action of the 80 piano pedals, but when the wings are turned upward they contact the lower edges of the levers 15 and prevent their operation; but a foot rest is still afforded the child, which is a source of comfort during extended 85 practice.

In the construction as above described, it will be noted that I have provided a device which may be readily adjusted into position or removed from the piano, and 90 one in which the parts are so adjustable vertically that the device may be used by children of different sizes, but while I have specifically described the construction and relative arrangement of the several elements 95 of my invention, I do not desire to be confined to the same, as such changes or modifications may be made as clearly fall within the scope of my invention without departing from the spirit thereof.

Having thus described my invention, what I claim as new and desire to secure by Letters Patent is:

A pedal operating device for pianos comprising a frame having two side members 105 spaced apart and secured by horizontally disposed rods, pedal-engaging levers pivotally connected between the sides to one of

the rods, vertically adjustable foot levers pivotally connected to the rod adjacent to the pedal-engaging levers, a thumb screw mounted in the former and contacting the 5 lower edge of the latter to regulate their vertical adjustment, together with a vertically adjustable heel rest having toothed supports mounted in the frame, and pawls pivoted to the sides of the frame for engag-

ing the teeth of said supports, as herein 10 shown and described.

In testimony whereof I affix my signature in presence of two witnesses.

HENRY C. KNIGHT.
